SAFETY MIXER

Frederick L. Craddock, Rochester, N. Y., assignor
to Mixing Equipment Company, Inc., Roches-
ter, N. Y., a corporation of New York

Application October 17, 1931, Serial No. 569,367

2 Claims. (Cl. 259—103)

This invention pertains to the same type of apparatus as is described in my United States Patent No. 1,817,353 dated August 4, 1931, for Safety mixer.

5 A broad object of the present invention is to discharge the cooling air in an improved manner, for instance, so as to avoid creating drafts in the air surrounding the mix. Such drafts are found to be troublesome where the mix is of a photographic emulsion or of other very delicate materials.

Other objects are to provide suitable air guiding surfaces and associated devices to direct the air discharge as desired.

15 Other objects may appear from the following detail description and may be pointed out in the appended claims.

Referring to the accompanying drawing:—

Fig. 1 is a side elevation of my improved mixer;
20 Fig. 2 is a cross section taken on the line 2—2 of Fig. 1;

Fig. 3 is a modification in which the air guide flanges are designed to discharge the cooling air in umbrella-like formation; and

25 Fig. 4 shows said air guide flanges reversed to discharge the cooling air in inverted, umbrella-like formation.

The numeral 1 indicates the right-hand side of any tank in which the mix is to be made and 30 upon which is fastened the clamp 3, made of cast aluminum, and detachably held in place by means of the hand-screw 5 which is provided with the hand-wheel 7.

The upper portion of the clamp 3 is provided 35 with a hemispherical recess 9 in which is placed a hemispherical mating casting 11, provided with a slot 13, in which is placed a washer 15, having two downwardly extending lugs 17 to prevent rotation of the washer 15 with respect to the casting 11.

A bolt, 19, having its head at the lower end, in a recess in clamp 3, extends upwardly through washer 15, and is secured by a nut 23.

40 Thus the clamp 3 and the casting 11 may be 45 adjustably locked in position with respect to each other by the nut 23. This adjustability is equivalent to that of a ball and socket joint and is universal for any practical position of the mixing propeller 25 in the tank 1.

50 The casting 11 extends as indicated and surrounds the lower portion of a motor 27, to which it is attached by screws 29, which enter the tapped holes 31, such as are found in standard motors of this type.

55 The casting 11 also extends downwardly to

form an outboard bearing which contains a stuffing box and bushing 32 for the hollow portion 33 of the propeller shaft 33—35. Members 33 and 35 are held together by a chuck 100, and wrench jaw grip flats 34 are formed on shaft 33. The 5 field yoke (or, in the case of an alternating current motor, the stator) 101 is provided with conventional end closure members 102 and 104, and a member of radial cooling flanges 103 which are surrounded by a cylindrical casing 105, thus forming 10 an air confining passage wherein heat generated in the motor may be transferred to air flowing through the passages 103. The heat laden air is discharged radially through the slots 106, best shown in Fig. 2, and the direction of the 15 discharge is further guided by the air guide flanges 1061 which are secured by screws 1061 to casting 11.

At an upper extension 107 of the motor shaft 39 there is mounted a centrifugal blower fan 109 20 surrounded by a casing 111, formed by an extension of casing 105, and having a hole 113 at its central portion. The fan thus draws in free air positioned far enough away from the mixing member to be free of spray or vapor.

25 When a motor of this improved type is operated in conventional applications other than in my improved mixer it has the advantage of being dustproof, fireproof and self-cooling, but when operated in combination with the other 30 parts of my mixer an additional advantage develops of blowing any emanations of the mix away from the motor 27 in such a manner as to disturb the air at the surface of the mix as little 35 as possible as well as avoiding the agitating of dust and disturbing the surrounding air.

A construction such as that shown in the drawing where both the cooling air in the motor and the propeller stream of the mixture in the tank are caused to discharge in directions substantially perpendicular to each other appears to have advantages of efficiency and convenience as compared to other possible arrangements.

40 By drawing air in axially at one end of the motor and discharging it radially at the other, a 45 very minimum of air disturbance occurs at the surface of the mix while perfect cooling is retained.

The modifications of Figs. 3 and 4 show a pair 50 of air guide flanges 130 which are curved so as to guide the heat laden air in umbrella formation when mounted as shown in Fig. 3 or in inverted umbrella formation when mounted as shown in Fig. 4. Flanges 130, by deflecting the 55 heat laden discharge air either upwardly or

downwardly, are designed to aid in controlling the air disturbance where such control is desirable under particular mixing conditions.

As an additional precaution for use in specially inflammable mixes, I provide a coupling flange 115 on casing 111 which carries one end of an intake hose 119 the remote end of which draws in fresh air from the outside of the building at the port-hole 121.

16 The direction of the air circulation through the various above described parts of the apparatus is indicated in the drawing by arrows.

I claim:—

1. An improved safety mixer provided with a shaft, an air jacketed motor in driving relation to the shaft, having a fan at one end, an air discharge port at the other end, a cored end bracket designed to deflect the air from the jacket toward the shaft and then away from the 20 shaft whereby the whole adjacent motor end may be cooled, said end bracket being provided

with narrow radial members designed for minimum interference with air flow and connecting the members at the upper and lower portions of the passage.

2. An improved safety mixer provided with a shaft, an air jacketed motor in driving relation to the shaft, having a fan at one end, an air discharge port at the other end, a cored end bracket designed to deflect the air from the jacket toward the shaft and then away from the 16 shaft whereby the whole adjacent motor end may be cooled, said end bracket being provided with narrow radial members designed for minimum interference with air flow and connecting the members at the upper and lower portions of 15 the passage, said bracket being provided with clamp means designed to be secured to a tank and to support the motor and associated parts through the medium of said narrow radial members.

FREDERICK L. CRADDOCK.
